CLOTHES BASKET HANGER

William H. Morris, Madison, Ala.

Application August 20, 1948, Serial No. 45,415

2 Claims. (Cl. 105—150)

1

This invention relates to clothes basket hangers, and more particularly to a hanger for suspending a basket of clothes from a clothes line.

The principal object of the invention is to provide a clothes basket hanger adapted to be easily engaged with a clothes line and slid therealong so that the basket of clothes may be shifted along the line while hanging clothes from the line.

Another object of the invention is to provide a clothes basket hanger which is capable of adjustment to baskets of different sizes.

Another object of the invention is to provide a clothes basket hanger that is easily assembled and disassembled.

A further object of the invention is to provide a clothes basket hanger which is extremely simple and inexpensive to manufacture.

Other objects and advantages of the invention will be apparent during the course of the following description.

In the accompanying drawings forming a part of this application, and in which like numerals are employed to designate like parts throughout the same:

Figure 1 is a side elevational view of a clothes basket suspended from a clothes line by means of the clothes basket hanger;

Figure 2 is an enlarged side elevational view of the clothes basket hanger;

Figure 3 is a top plan view of the clothes basket hanger;

Figure 4 is a fragmentary end elevational view of the clothes basket hanger;

Figure 5 is a sectional view taken on the line 5—5 of Figure 2.

Referring in detail to the drawings, the clothes basket hanger comprises a pair of horizontally-disposed arms 10 and 11. The arm 10 is provided with a longitudinally-extending, arcuate or curved portion 12, and the arm 11 is provided with a longitudinally-extending, arcuate or curved portion 13. Arranged in spaced relation along the arm 10 is a plurality of openings 14, there being a plurality of spaced openings 15 arranged on the arm 11 for a purpose to be hereinafter described. The arms 10 and 11 are arranged so that the arcuate portion 13 of arm 11 is slidably and snugly received in the arcuate portion 12 of arm 10. For releasably locking the arms 10 and 11 together, a headed bolt 16 is inserted through one of the openings 14 in the arm 10 and a registering opening 15 in the arm 11. The bolt 16 is provided with a threaded end 17 and threaded thereon is a lock-

2

ing member embodying a nut 18. Circumposed on the bolt 16 and arranged between the nut 18 and the arm 11 is a resilient means embodying a coil spring 19 for biasing the arms 10 and 11 together. The end of the arm 10 is flat and is arranged in side-by-side relation with respect to the upper flat end 20 of a tapered, vertically-disposed suspension rod 21. The suspension rod 21 has its upper end bent at 22 and turned downward to form bearings for the grooved roller 23, said roller being mounted on a pin 24 which extends through arm 10 and through the bearings of the suspension rod 21. A washer 25 is positioned on the pin 24 on each side of the roller 23, and a lock nut 26 is threaded on the threaded end 27 of the pin 24 for locking the arm 10, suspension rod 21 and roller 23 in assembled relation.

The end of the other arm 11 is flattened and is arranged in side-by-side relation with respect to the upper flat end 28 of a tapered suspension rod 29. The suspension rod 29 has its upper end bent at 30 and turned downward to form bearings for the grooved roller 31, the roller 31 being supported in the bearings by a pin 32 and lock nut 33.

The lower ends of the suspension rods 21 and 29 each dependently carry a hook 34 and 35, respectively, for engagement with the bails 36 of a clothes basket 37 for supporting the latter. A receptacle 38 for containing clothes pins may be suspended by its handle 39 from the hook 34.

In use, the hanger is arranged so that the grooved rollers 23 and 31 engage the clothes line 9 which is supported by the post 8. The basket 37 containing clothes is suspended from the hooks 34 and 35 on the lower ends of the suspension rods 21 and 29, and by means of this construction the hanger may be readily connected to a clothes line 9 and removed therefrom, the basket 37 being movable upon the clothes line from place to place. For supporting baskets 37 of different sizes, the space between the suspension rods 21 and 29 can be varied by first disassembling the bolt 16 from the apertured arms 10 and 11, then adjusting the arms 10 and 11 to the proper position, and then re-inserting the bolt 16 through a pair of registering apertures 50 in the arms 10 and 11.

While I have shown and described what is now thought to be a preferred embodiment of the invention, it is to be understood that the same is susceptible of other forms and expressions. Consequently, I do not limit myself to the precise

structure shown and described hereinabove except as hereinafter claimed.

I claim:

1. In a device for suspending a clothes basket from a clothes line, a pair of vertically-disposed suspension rods, a roller mounted on the upper end of each of said suspension rods for engagement with said clothes line, means on each of said suspension rods for engagement with said clothes basket for supporting the latter, and means operatively connecting said rods together, said last-named means comprising a first arm provided with a plurality of apertures secured to one of said suspension rods, a second arm provided with a plurality of apertures secured to the other of said suspension rods, said arms being arranged in side-by-side relation and mounted for longitudinal movement relative to each other, and a securing element adapted to be inserted through a pair of registering apertures in said arms.

2. In a device for suspending a clothes basket from a clothes line, a pair of vertically-disposed suspension rods, a roller mounted on the upper end of each of said suspension rods for engagement with said clothes line, means on each of said suspension rods for engagement with said clothes basket for supporting the latter, and means operatively connecting said rods together, said last-named means comprising a first arm provided with a plurality of apertures secured

5

10 to one of said suspension rods, a second arm provided with a plurality of apertures secured to the other of said suspension rods, said arms being arranged in side-by-side relation and mounted for longitudinal movement relative to each other, a securing element adapted to be inserted through a pair of registering apertures in said arms, a locking member positioned on an end of said securing elements, and resilient means interposed between said locking member and said arms for biasing said pair of arms together.

WILLIAM H. MORRIS.
